ROUGH ROUNDING MACHINES

Alphonse C. Kulik, Ipswich, Mass., assignor to United Shoe Machinery Corporation, Flemington, N. J., a corporation of New Jersey

Application July 18, 1955, Serial No. 522,589

13 Claims. (Cl. 12—85)

This invention relates to sole rounding machines, and is illustrated herein as embodied in an improved work rest and mounting therefor adapted for use in a machine of the type disclosed in United States Letters Patent No. 2,782,432, granted February 26, 1957 upon my application Serial No. 480,842, filed on January 10, 1955.

Rough rounding machines of this type may be required to round sole edges of a thickness varying from less than a quarter of an inch up to one inch, or even more. A shoe being rounded is supported at the upper side of the sole by a feed point and a crease guide, the feed point being arranged to resist the thrust of a reciprocatory rounding cutter. The shoe is yieldingly held against the feed point and crease guide by a bottom rest which cooperates with the feed point to impart a feeding movement to the work and, in addition, positions the shoe so that the rounding cut is directed at the desired angle to the bottom of the sole.

If the bottom rest is set appropriately for a work piece of one thickness, a heavier work piece cannot be as readily presented to the machine and may be gripped with an excessive pressure. Similarly, a lighter work piece may not be gripped firmly enough to afford a satisfactory feeding action. Accordingly, with any appreciable change in thickness of the work, resetting of the bottom rest is required and ordinarily, in prior machines of this type, for any such readjustment of the bottom rest a corresponding adjustment of the yielding means, from which the gripping effect of the bottom rest is derived, is necessary to avoid a change in the feeding action of the machine.

With the foregoing in view, an object of the invention is to provide an improved bottom rest structure which can be readily adjusted either to accommodate a wide range of sizes of work, or to vary the pressure with which the bottom rest bears against the shoe, and which does not require readjustment for either condition when a change in the other has been made.

To this end, and in accordance with one feature of the present invention, there is provided mechanism for controlling the bottom rest of the illustrated machine including, with means for urging the rest toward the support which resists the thrust of the rounding cutter and means for determining the normal spacing of the rest from the support, operator controlled means for selectively operating each of said above mentioned means independently to vary the bearing pressure of the rest against the shoe bottom and the normal spacing of the rest from the support.

More specifically, and in accordance with a further feature of the invention, the above-mentioned mechanism includes, with an operating member which is movable in one direction to effect a change in the normal spacing of the bottom rest from the support, which member is also mounted for yielding movement in another direction to cause the rest to press against the shoe bottom, operator controlled means for moving the member in the said

one direction in order to vary the normal spacing of the rest from the support, and a second operator controlled means mounted for movement bodily with, and also with respect to, the first-mentioned operator controlled means, for the purpose of adjusting the resistance to the yielding movement of the member, and hence the pressure with which the rest bears upon the shoe bottom.

These and other features of the invention will now be described in detail in connection with the accompanying drawings and will be pointed out in the appended claims.

In the drawings,

Fig. 1 is a side elevation of a portion of an illustrative machine embodying the invention;

Fig. 2 is a sectional plan view of the structure shown in Fig. 1, certain parts having been broken away, and the section being taken along the line II—II of Fig. 1; and

Fig. 3 is an elevation of the bottom rest and its mounting as viewed obliquely from the right of the machine in the direction of the arrow in Fig. 2.

A shoe to be operated upon in the illustrated machine is presented thereto with the upper surface of its welt, or the corresponding portion of the shoe if it is not a welt shoe, in engagement with and supported by a crease guide

25 10 (Fig. 1) and a feed point 12, these members being arranged to guide the shoe and support it against the thrust of a reciprocatory chopping knife 14. The position of the rounding cut and hence the width of the sole edge extension, is determined in the shank of the shoe by the crease guide 10 and in the forepart portion of the shoe by a forepart gage 16, as is well understood in this art, and as disclosed in the patent referred to above, to which reference may be made for a complete description and disclosure of the construction and operation of the parts

35 referred to thus far.

The shoe is yieldingly held against the crease guide 10 and feed point 12 by a bottom rest 18 and an auxiliary rest 20 which insure that the shoe, with its bottom seated upon both rests, will be presented to the knife at the proper angle thereto. The rest 18 is adjustably secured

40 by a screw 22 to a carrier 24 which is mounted to swing toward and away from the guide 10 and feed point 12, in order to accommodate work of different thicknesses,

45 upon a stud 26 carried by a block 28. The block has an arcuate portion, T-shaped in cross-section, which is concentric with the upper edge of the rest 18 and is ar-

50 ranged to slide in a complementary guideway formed in a support 30, so that the rest 18 is brought into complete contact heightwise thereof, with the shoe bottom in response to pressure therebetween. A spring pressed ball

55 32, mounted in the block 28 and normally seated in a shallow recess in the support 30, tends to hold the rest 18 in its normally erect position and to return the rest to this position if it is displaced to either side thereof. The support 30 is fixed to a pair of rods 34, 34 which are

50 mounted to slide horizontally in bosses 36 which protrude forwardly from a cover plate 37. This plate is fixed

60 upon the frame 38 of the machine by screws 39. Horizontal reciprocatory motion is imparted to the support 30 in timed relation to the oscillating movement of the feed point 12, as disclosed in United States Letters Patent

65 No. 2,543,760 granted March 6, 1951 upon an application of J. C. Cantley, whereby synchronized feeding movements from right to left are imparted to the rest 18 and feed point 12, and to a shoe being operated upon.

The auxiliary rest 20 is slotted to receive a screw 40 (Fig. 3) by which it is mounted, for adjustment relatively to the rest 18 for the purpose of establishing the desired angle of the rounding cut with respect to the shoe bottom,

70 upon a carrier 42 which is mounted to swing horizontally on a stud 44, the latter being fixed to the support 30.

The free end of a spring 46, which is coiled about a bushing 48 fastened to the stud 44, is inserted into a hole in the carrier 42 and causes the rest 20 to be biased rearwardly, such movement of the rest being limited by the engagement of a lug 50, fixed to the carrier 42, with the carrier 24.

The bottom rest 18 is controlled, both as to its normal position with respect to the guide 10 and feed point 12, and the pressure which it exerts upon the shoe bottom, by the following mechanism. An arm 52 (Fig. 2) fixed upon the carrier 24, is connected by a link 54 to the upper arm of a bell crank 56 comprising a shaft 58 which is mounted to swing about a vertical axis upon a bracket 59. The bracket is fixed to the frame 38 by the screws 39 at the left hand side of the plate 37. The lower arm of this bell crank has pivotally mounted thereon a square block 60 which is received in a slot in a forwardly extending arm 62 which is fixed to the upper end of a shaft 64, rotatably mounted upon a bracket 66, the latter being fixed to the frame 38. Upon the lower end of the shaft 64 there is fixed a gear segment 68 in mesh with a worm 70 which is mounted for rotation and yielding sliding movement axially thereof upon a tubular shaft 72. Rotation of the worm with respect to the shaft 72 is prevented by a spline or key 74 which fits freely in a groove in the worm, so as to permit the sliding movement of the latter upon the shaft.

The worm is normally biased into engagement with a bearing 76 for the left hand end of the shaft 72 by a spring 78, the latter being compressed between the worm and a cap or abutment 80 which is mounted upon the shaft 72 for adjustment lengthwise thereof to vary the strain in the spring. The abutment is freely received in a bearing 82 which, like the bearing 76, is integral with the bracket 66. The abutment 80 is adjusted by turning a rod 84 which is rotatably mounted within and coaxially of the shaft 72, the right hand end of the rod having formed thereon a screw 86, which is threaded into the abutment 80. The abutment is prevented from turning on the shaft 72 by a pair of pins 88, 88 which are fixed to the abutment and slide within grooves 90 formed oppositely to each other in the shaft 72 and extending lengthwise thereof.

It will now be evident that when the worm 70 is seated upon the bearing 76, in response to the pressure of the spring 78, the rest 18, through the connections between the worm and the carrier 24, will be yieldingly held in a predetermined position with respect to or at a normal spacing from the guide 10 and feed point 12.

In order to vary the normal position of the rest 18, in accordance with the thickness of the work to be presented to the machine, the worm 70 is rotated by turning a hand wheel 92 which is fixed upon the left hand end of the shaft 72 by means of a screw 94 which is threaded into the hand wheel and bears against a shoulder formed on the shaft.

The rod 84 is turned to adjust the spring 78, and hence to vary the pressure with which the rest 18 bears against the shoe bottom, by rotating an arm 96 which is pinned to the left hand end of the rod 84. The arm is releasably held in adjusted position by a spring pressed detent 98 which is arranged to enter any one of a series of holes 100 formed in the hand wheel 92.

A further provision for varying the yielding action of the rest 18 is afforded by a notch 101 formed in the arm 52 in such a position as to receive the left-hand end of the rest. If a light or delicate yielding action of the rest 18 is desired it may be set, utilizing a slot in the rest for the screw 22, so far forwardly of the arm 52 that the rest, when deflected, does not engage the arm. This setting of the arm is commonly employed when the sole material to be rounded is of a yielding nature, as in the case of crepe rubber. In other instances, especially when the sole material is thin and rigid, it may be desirable to adjust the rest 18 so that its left-hand end is seated

against the notched portion of the arm 52, in which case the rest 18 has a relatively stiff yielding action.

The rests 18 and 20 are retracted from their normal positions, to facilitate presentation of a shoe to the machine, by the following connections. There is fixed to the carrier 42 for the auxiliary rest 20 an arm 102 upon which is fixed a rod 104 carrying at its upper end a block 106. This block is disposed in the path of movement of a plunger 108 which is mounted to slide forwardly and rearwardly of the machine in the frame 38 and is biased toward its rearward position by a spring 110. The rearward position of the plunger is determined by an adjustable stop 112 which is threaded in the frame 38. The plunger is operated by a bell crank 114 which is pivoted at 116 upon the frame 38 and has connected thereto a rod 118 which is driven by a treadle (not shown). By depressing the treadle, the plunger 108 is moved forwardly and, through the above-described connections, causes the retraction of the rest 20, an equal retraction being imparted to the rest 18 by the lug 50 which at this time bears against the carrier 24.

The operation and use of the illustrative structure will now be summarized. The rest 18 is first adjusted forwardly and rearwardly of the machine to provide the desired yielding action, either light or stiff, and the rest 20 is then adjusted so that when the shoe bottom is seated upon both rests the sole edge will be trimmed at the desired angle with respect to the bottom. The hand wheel 92 is next turned in the appropriate direction to cause the normal spacing of the rest 18 from the guide 10 and feed point 12 to be somewhat less than the thickness of the sole to be rounded. After the latter adjustment has been made, a relatively slight depression of the treadle will be adequate to retract the rest 18 enough to facilitate the presentation of the shoe to the machine, with the guide 10 seated in the welt crease of the shoe, and the shoe bottom seated upon the rests 18, 20. Upon the release of the treadle, the rest 18 is advanced into contact with the shoe bottom by the action of the spring 78, there now being a small amount of clearance between the worm 70 and the bearing 76, this clearance corresponding to the distance by which the rest will have been displaced rearwardly from its normal position by the work.

Sufficient bearing pressure of the rest 18 against the shoe bottom to afford an effective feeding action is procured by retracting the detent 98 away from the hand wheel 92 and turning the arm 96 to vary the strain of the spring 78 as desired.

As the arm 96 is mounted within, and for movement with, the hand wheel 92 and shaft 72, it is evident that the spacing of the rest 18 from the guide 10 and feed point 12 can be varied at will without changing the strain of the spring 78, and hence without affecting the pressure with which the rest 18 will bear against the shoe bottom. Similarly, for any setting of the rest 18 the arm 96 may be turned to effect an adjustment of the strain in the spring 78 and hence the pressure with which the rest 18 bears against the shoe bottom without affecting the setting of the rest.

Having thus described my invention, what I claim as new and desire to secure by Letters Patent of the United States is:

1. In a rough rounding machine having a rounding cutter, a support, a bottom rest between which and said support a shoe to be operated upon is presented to said cutter, mechanism for controlling said rest comprising means for urging it toward said support and means for determining its normal spacing from said support, and operator controlled means for selectively operating each of said above-mentioned means independently to vary separately the bearing pressure of said rest against the shoe bottom and the normal spacing of said rest from said support.

2. A rounding machine having a rounding cutter, a support, a bottom rest between which and said support

a shoe to be operated upon is presented to said cutter, said rest being mounted for movement toward and away from said support, mechanism for controlling said rest comprising yielding means for urging it toward said support and means for limiting movement of said rest toward said support, operator controlled means for operating said last-mentioned means to vary the normal spacing of said rest from said support, and a second operator controlled means mounted for bodily movement with and also with respect to said first-mentioned operator controlled means for adjusting said yielding means.

3. A rough rounding machine having a rounding cutter, a support, a bottom rest between which and said support a shoe to be operated upon is presented to said cutter, said rest being mounted for movement toward and away from said support, mechanism for controlling said rest comprising an operating member which is mounted for movement in one direction to effect a change in the normal spacing of said rest from said support, said member being mounted for movement in another direction in response to movement of said rest toward and away from said support, yielding means for resisting movement of said member in response to movement of said rest away from said support, operator controlled means for moving said member in said one direction to vary the normal spacing of said rest from said support, and a second operator controlled means mounted within said first-mentioned operator controlled means for movement with and with respect thereto for adjusting said yielding means.

4. In a rough rounding machine, a rounding cutter, a support against which a shoe to be operated upon is presented to said cutter, a rest for holding the shoe against said support by engagement with the bottom of the shoe, said rest being mounted for movement toward and away from said support, and mechanism for controlling said rest comprising a member mounted for movement in one direction in response to retractive movement of said rest from said support and in a second direction to vary the normal spacing of said rest from said support, means for yieldingly resisting movement of said member in said one direction whereby said rest is biased against the shoe, and operator controlled means for moving said member in said second direction to adjust the normal spacing of said rest from said support.

5. In a rough rounding machine, a rounding cutter, a support against which a shoe to be operated upon is presented to said cutter, a bottom rest mounted for movement toward and away from said support, mechanism for controlling said rest comprising a member mounted for rotative movement and for yielding sliding movement lengthwise of its axis of rotation, operator controlled means for rotating said member to adjust the normal spacing of said rest from said support, yielding means for resisting sliding movement of said member in response to retractive movement of said rest from said support, and means for adjusting said yielding means whereby the bearing pressure of said rest upon the shoe is varied.

6. In a rough rounding machine, a rounding cutter, a support against which a shoe to be operated upon is presented to said cutter, a bottom rest mounted for movement toward and away from said support, mechanism for controlling said bottom rest comprising a rotatable shaft, a member mounted upon said shaft to rotate therewith and to slide lengthwise thereof in response to retractive movement of said bottom rest from said support, yielding means acting upon said member for resisting retractive movement of said rest, and means carried by said shaft for adjusting said yielding means to vary the resistance of said member to the retractive movement of said rest.

7. In a rough rounding machine, a rounding cutter, a support against which a shoe to be operated upon is presented to said cutter, a bottom rest mounted for movement toward and away from said support, mechanism for controlling said bottom rest comprising a rotatable

shaft, a member mounted upon said shaft to slide lengthwise thereof in response to movement of said rest away from said support, said member also being mounted upon said shaft to rotate therewith to vary the normal spacing of said rest from said support, an abutment mounted upon said shaft for movement lengthwise thereof, a spring compressed between said abutment and said member, and operator controlled means mounted within said shaft for adjusting said abutment lengthwise of said shaft thereby to vary the pressure of said bottom rest against the shoe.

8. In a rough rounding machine having a rounding cutter, a support against which a shoe to be operated upon is presented to said cutter, and a rest for holding the shoe against said support by engagement with the bottom of the shoe, operator controlled means for retracting said rest from said support to facilitate insertion of a shoe therebetween, and mechanism for controlling said rest comprising a stop, a member mounted for yielding sliding movement away from said stop in response to retractive movement of said rest, said member being rotatable to vary the normal spacing of said rest from said support, and operator controlled means for rotating said member.

9. In a rough rounding machine having a rounding cutter, a support against which a shoe to be operated upon is presented to said cutter and a bottom rest mounted for movement toward and away from said support, operator controlled means for retracting said rest from said support, and mechanism for urging said rest toward said support comprising geared members one of which is mounted to slide and to rotate, a spring for yieldingly resisting sliding movement of said sliding and rotating member in one direction whereby the shoe is held against said support by said rest, a stop for limiting movement of said sliding and rotating member in response to the pressure of said spring thereagainst, and means for rotating said sliding and rotating member to adjust the normal spacing of said rest from said support.

10. In a rough rounding machine, a rounding cutter, a support against which a shoe to be operated upon is presented to said cutter, a bottom rest mounted for movement toward and away from said support, means for adjusting said bottom rest comprising a worm and a geared member meshing with said worm, a shaft upon which said worm is mounted to slide in response to movement of said rest away from said support, a stop for limiting the sliding movement of said worm in one direction, means for yieldingly holding said worm against said stop whereby said rest is normally held at a predetermined distance from said support, and means for rotating said shaft and worm to vary the normal spacing of said rest from said support.

11. In a rough rounding machine having a rounding cutter and a support against which a shoe to be operated upon is presented to said cutter, a bottom rest mounted for movement toward and away from said support, mechanism for positioning said bottom rest comprising a worm mounted to slide and rotate and a geared member meshing with said worm, means for rotating said worm to vary the normal position of said rest with respect to said support, a spring acting upon said worm to bias said rest against a shoe disposed between said rest and said support, and means for adjusting the strain of said spring to vary the pressure of said rest against the shoe.

12. In a rough rounding machine having a rounding cutter and a support against which a shoe to be operated upon is presented to the cutter, a rest adapted to engage the shoe bottom and arranged to hold the shoe against said support, mechanism for adjusting said rest comprising a rotatable shaft, a worm splined to said shaft, connections between said worm and said rest comprising a geared member meshing with said worm, a spring acting upon said worm to cause said rest to be biased against a shoe disposed between said rest and said support, an abutment for said spring mounted for adjustment axially

of said shaft toward and away from said worm, and means mounted within said shaft for adjusting said abutment thereon to vary the strain of said spring without affecting the position of said rest with respect to said support.

13. In a rough rounding machine, a rounding cutter, a support against which a shoe to be operated upon is presented to said cutter, a bottom rest mounted for movement toward and away from said support to hold the shoe thereagainst by engagement with the shoe bottom, operator controlled means for retracting said rest from said support, means for biasing said rest toward said support comprising a worm and a geared member meshing with said worm, a rotatable shaft upon which said

5

10

worm is splined for movement axially thereof, a cap mounted upon said shaft to slide axially thereof, a spring interposed between said cap and said worm, and a rod rotatably mounted within said shaft and threaded into said cap for positioning the latter along said shaft to vary the strain of said spring whereby the pressure of said rest against the shoe bottom is varied.
